UNITED STATES PATENT OFFICE.

ALBERT FORBES CONANT, OF NANTANT, MASSACHUSETTS.

CLOSET OR CASE.

SPECIFICATION forming part of Letters Patent No. 729,279, dated May 26, 1903.

Application filed May 1, 1902. Serial No. 105,539. (No model.)

To all whom it may concern:

Be it known that I, ALBERT FORBES CONANT, a citizen of the United States, residing in Nantant, in the county of Essex and State of Massachusetts, have invented an Improvement in Closets or Cases, of which the following description, in connection with the accompanying drawings, is a specification, like letters on the drawings representing like parts.

This invention relates to a closet, cabinet, bookcase, or like article provided with a series of shelves, and has for its object to provide for adjustably supporting the said shelves in a manner as will be described, whereby any one or all of a series of shelves may be raised or lowered in a substantially short time and without necessitating the removal of the objects upon said shelves. For this purpose the closet, cabinet, or other case is provided at its opposite ends with upright guideways in which are located a series of supports or sections adapted to rest one on the other and upon which the ends of the shelves rest between said guideways, as will be described.

Figure 1 is a front elevation of one form of cabinet or closet embodying this invention; Fig. 2, a section on the line 2 2, Fig. 1; Fig. 3, a section on the line 3 3, Fig. 1; and Fig. 4, a detail in section on the line 4 4, Fig. 3, to be referred to.

In the present instance I have illustrated my invention as embodied in a cabinet, closet, or bookcase comprising a base *a*, front *b*, back *c*, sides *d*, and top *e*, the front *b* having glass doors *f*.

In accordance with this invention the cabinet, &c., is provided at its opposite sides with vertically-arranged guideways, which may be formed, as shown in the present instance, by pieces or strips *g* of wood, metal, or other suitable material suitably secured to the front and back of the cabinet. The guideways referred to have extended into them the ends of supporting bars, pieces, or sections *h*, which may be of the same or varying sizes and upon which the ends of the shelves *i* rest. The supporting bars or sections *h* rest one upon the other (see Fig. 2) and form a solid support for the shelves, which rests upon the base *a* and extends upward substantially to the

top of the case. The supporting bars or sections *h* are individually movable and each section or bar can be removed from its guideway by tipping or inclining the same, so as to clear the retaining-walls *g* of said guideway.

The shelves *i* may be adjusted with relation to each other by inserting one or more of the supporting bars or sections *h* below it, and when it is desired to adjust a shelf the latter is pushed bodily upward a distance sufficient to leave space for the insertion of a supporting bar or section *h* below the shelf thus raised, after which the latter can be lowered upon the uppermost supporting bar or section.

In the adjustment of the shelf the supporting bars or sections above the shelf, which is raised, slide up in their guideways and carry with them the shelf or shelves above the one which is raised. The adjustment of the shelves can be readily and easily accomplished without removing the dishes, books, or other articles upon those shelves which are moved upward to effect the adjustment.

The invention is applicable to china-closets which are built into a house, and therefore stationary, or to china-closets which are portable. It is also equally applicable to bookcases, cabinets, and like receptacles. It will be noticed that when a shelf is raised the other shelves above it are firmly supported by the bars or sections *h*, resting on the shelf which is raised.

In the present instance the guide strips or pieces *g* are shown as projecting from the front and back of the case, and in this case the ends of the shelves are notched, as represented in Fig. 3, so that the end of the shelf may extend beyond the guide-strips and rest upon the supporting bar or section, as shown in Fig. 4; but I do not desire to limit my invention in this respect.

I claim—

1. A closet or case of the character described, provided at its ends with upright guideways, shelf-supporting sections bodily movable in said guideways, and shelves having their ends extended beyond the front walls of said guideways and between adjacent sections to rest upon a lower section and

support an upper section, substantially as described.

2. A closet or case of the character described, provided at its opposite ends with upright strips or pieces forming upright guideways, supporting bars or sections bodily movable in said guideways and normally resting one on the other, and shelves having their ends interposed between adjacent sections

and resting on the lower one of said sections, substantially as described.

In testimony whereof I have signed my name to this specification in the presence of two subscribing witnesses.

ALBERT FORBES CONANT.
